OPTICAL GRINDING AND POLISHING MACHINE
James P. Charlton, P.O. Box 95, Dillwyn, Va.
Filed Dec. 7, 1962, Ser. No. 242,953
13 Claims. (Cl. 51—26)

This invention relates to grinding and polishing machines for forming high precision optical surfaces, and more particularly to an optical grinding and polishing machine wherein an optical blank is moved over a rotating abrading die in a predetermined path of movement.

A main object of the invention is to provide a novel and improved grinding and polishing machine of the type in which an upper optical blank is supported in engagement with a rotating second optical blank, with a layer of suitable abrasive material interposed therebetween so that the adjacent surfaces of the blanks are formed in accordance with one another, with the thickness of the abrasive layer, and with the amount of energy spent in removing material from the blanks, the machine being provided with means for rotating the upper blank and simultaneously moving it in a predetermined path, the movement of said upper blank being accomplished by means of amplitude-modulated strokes in a plane perpendicular to the axis of rotation of the lower blank and wherein the path of movement of the axis of the upper blank has substantially a closed loop configuration.

A further object of the invention is to provide an improved optical grinding and polishing machine of the type wherein an upper optical blank is supported with its bottom surface in abrasive contact with the top surface of a rotating lower blank, the machine being arranged to move the upper blank substantially horizontally while rotating same with a movement whose path is the resultant of horizontal reciprocation of said upper blank and simultaneous lateral movement thereof in a direction substantially perpendicular to the direction of its horizontal reciprocation.

A still further object of the invention is to provide an improved optical grinding and polishing machine of the type employing a continuously rotating horizontal lower optical blank which rotates on a stationary vertical axis and means to support an upper rotating optical blank against the top surface of the lower blank, with suitable abrasive material interposed between the blanks, with means to simultaneously reciprocate the upper blank horizontally in one direction and to reciprocate it laterally in a direction substantially perpendicular to the first-named direction of horizontal reciprocation, whereby to modulate the movement of the upper blank in a manner to provide maximum uniformity of the abrading action on the adjacent surfaces of the blanks, the machine being provided with easily operated means to adjust the elements which define the various parameters of the figure of movement of the upper blank.

A still further object of the invention is to provide an improved optical grinding and polishing machine of the type employing a rotating lower blank which revolves on a fixed vertical axis and means to support a rotating upper blank in abrasive contact therewith and to move the upper blank horizontally in a predetermined geometrical pattern so as to produce a relatively high degree of uniformity of abrasive action on the adjacent surfaces of the blanks, the machine being relatively compact in size, being reliable in operation, being durable in construction, and being easy to adjust.

Further objects and advantages of the invention will become apparent from the following description and claims, and from the accompanying drawings, wherein:

FIGURE 1 is a top plan view of an improved optical

2

grinding and polishing machine constructed in accordance with the present invention.

FIGURE 2 is a side elevational view of the machine illustrated in FIGURE 1.

5 FIGURE 3 is a transverse vertical cross sectional view taken substantially on the line 3—3 of FIGURE 2.

FIGURE 4 is an enlarged horizontal cross sectional view taken substantially on the line 4—4 of FIGURE 2.

10 FIGURE 5 is a longitudinal vertical cross sectional view taken substantially on the line 5—5 of FIGURE 1, and drawn to a substantially enlarged scale.

FIGURE 6 is a horizontal cross sectional view taken substantially on the line 6—6 of FIGURE 2.

15 FIGURE 7 is a horizontal cross sectional view similar to FIGURE 6, but showing the parts at a different portion of the operating cycle of the machine.

FIGURE 8 is an elevational detail view, partly in cross section, of the main drive crank frame of the machine of FIGURES 1 to 7, and the parts immediately adjacent thereto.

20 FIGURE 9 is a horizontal cross sectional view taken substantially on the line 9—9 of FIGURE 8.

FIGURE 10 is a side elevational view, similar to FIGURE 8, and partly in cross section, showing the parts in a somewhat different position in the cycle of operation of the machine.

25 FIGURE 11 is a horizontal cross sectional view taken substantially on the line 11—11 of FIGURE 10.

30 FIGURE 12 is a vertical cross sectional view taken through the upper optical blank, and illustrating the manner in which the upper optical blank moves over the forming surface of the subjacent optical blank, for example, from the position thereof shown in FIGURE 7 to the position thereof shown in FIGURE 6.

35 FIGURE 13 is a fragmentary transverse vertical cross sectional view, taken substantially on the line 13—13 of FIGURE 5.

FIGURE 14A is a diagram illustrating the two paths 40 of movement of the axis of the upper blank in two different positions of adjustment of a horizontal crank rod of the oscillating mechanism for the upper blank supporting angle bars of the machine of FIGURES 1 to 13.

FIGURE 14B is a diagram illustrating the two paths 45 of movement of the axis of the upper blank, with the crank rod adjustments of FIGURE 14A but with the vertical pivot axis of the angle bars in a different position of adjustment.

FIGURE 14C is a diagram illustrating the two paths of 50 movement of the axis of the upper blank, with the crank rod adjustments of FIGURE 14A, but with the vertical pivot axis of the angle bars in a further different position of adjustment.

Referring to the drawings, 14 generally designates an 55 improved optical grinding and polishing machine according to the present invention. The machine 14 comprises a base 15 on which is mounted a supporting frame 16 provided at one end with a pair of vertically spaced bearing brackets 17, 17 in which is supportingly journaled a vertical shaft 18 on the top end of which is secured a circular tray 19. Secured to the shaft 18 immediately subjacent the tray 19 is a drive pulley 20. Secured in the central portion of the tray coaxially with the shaft 18 is a block 21 provided with upstanding pins 22 defining an enclosure receiving a lower blank 23, concentrically secured on a spherically rounded bottom supporting disc 69, which is thus coaxially supported on the block 20 for rotation therewith.

As shown in FIGURE 1, the block 21 is substantially 70 square in shape, the upstanding pins 22 being located at the corner portions of the block, and the circular lower blank 23 being received inside the pins, the pins engaging

the periphery of the circular blank 23 so as to keep it centered relative to block 21 and the axis of rotation of the assembly comprising shaft 18 and tray 19. Spacing blocks 24 are interposed between the lower blank 23 and the supporting block 21, to define a space therebetween for the free passage of liquid containing abrasive material, said passage communicating with a central bore 25 provided in the supporting block 21, said bore 25 receiving the depending universal joint connection bracket 70' of disc 69' and communicating with radial passages 26 provided at the bottom of the supporting block 21, said radial passages being in communication with the outer portions of tray 19. An annular drain trough 27 is supported by frame 16, for example, by a bracket 28' secured on said frame, the drain trough 27 surrounding shaft 18 and being located beneath drain apertures 28 provided in the central portion of tray 19. Connected to the peripheral portion of the annular drain trough 27 is a drain conduit 29 leading to a suitable receiving container.

Designated at 30 is an electric motor which is vertically mounted in the frame 16 and which has an output shaft coupled through a transmission unit 31 to a cone pulley 32. Cone pulley 32 is drivingly coupled to a vertically mounted cone pulley 33 which is secured on a vertical shaft 34 journaled in the top portion of frame 16, a pair of relatively small pulleys 35, 35 being secured to the top portion of shaft 34, adjacent to each other, as shown in FIGURE 3.

Cone pulley 32 is drivingly coupled to cone pulley 33 by a belt 36. Designated at 37 is a vertical shaft which is rotatably supported in a vertical sleeve 38 and a bottom bearing bracket 39 secured to the end of frame 16 opposite the shaft 18, as shown in FIGURE 2. Secured on the upper portion of shaft 37 are a pair of relatively large pulleys 40, 40 which are drivingly coupled to the pulleys 35, 35 by respective drive belts 41, 41. A cone pulley 42 is secured on shaft 37 below the pulleys 40, 40. Cone pulley 42 is drivingly coupled by a belt 43 to a cone pulley 44 secured on a vertical shaft 45 journaled in the top portion of frame 16. Cone pulley 44 is drivingly coupled to the large drive pulley 20 associated with the tray 19 by a belt 46.

It will be thus readily apparent that the motor 30 simultaneously drives the tray 19 and the vertical shaft 37.

Rigidly secured to the top end of the shaft 37 is a horizontal arm 47 of inverted V-shaped cross section. Designated generally at 48 is a crank frame comprising a bottom horizontal arm 49 of V-shaped cross section which is slidably received in the arm 47 and which is clampingly secured thereto in adjusted position relative to the vertical shaft 37 by a clamping assembly 50.

The clamping assembly 50 comprises an outer sleeve member which slidably embraces the nested members 47 and 49, being provided with top clamping flanges 51, 51, and being provided with a bottom vertical clamping screw 52 which is threadedly engaged through the bottom corner of the clamping sleeve 50 and which is clampingly engageable with the bottom corner of a V-shaped clamping plate 53 which is disposed subjacent the arm 47, the V-shaped clamping plate 53 being received in the generally V-shaped bottom portion of the clamping member 50, and the top edges of the member 53 being clampingly engageable against the respective walls of the inverted V-shaped member 47.

Vertical angle bars 54, 55 are rigidly secured to the opposite ends of the arm 49, a transverse angle bar 56 being secured to the top end of the bar 55. Respective horizontal angle bars 57, 57 are rigidly secured to the opposite end portions of the transverse angle bar 56, the angle bars 57, 57 extending parallel to the bottom arm 49 and being secured at the ends thereof opposite the angle bar 56 to the top portion of the angle bar 54.

The angle bars 57, 57 are arranged with their vertical flanges disposed inwardly, defining a guide slot extending longitudinally of the frame 48. Slidably supported on the

parallel angle bars 57, 57 are a pair of parallel angle bars 58, 58 between the intermediate portions of which is welded a vertical upstanding bearing sleeve 59 through which rotatably extends a vertical shaft 60. Rigidly secured to the bottom end of the shaft 60 is an upwardly facing horizontal V-shaped arm 61 to which is adjustably secured a pivot bracket 62, the bracket 62 being generally V-shaped and nestingly receiving the arm 61 and being provided with means to clamp same to the arm 61 at an adjusted position along the length of said arm. The bracket member 62 is provided with the depending pivot ball 63 which is received in a ball socket provided in a pivot bearing member 64 which is adjustably mounted on a horizontal rod 65 pivotally connected to the bottom arm 49. Thus, the arm 49 has rigidly secured thereto a vertical upstanding pivot shaft 66 on which is rotatably engaged a vertical bearing sleeve 67 which is rigidly secured to the end of the rod 65.

As will be apparent from FIGURE 5, the vertical drive shaft 37 rotates the frame 48 around the axis of shaft 37, whereby the vertical pivot shaft 66 moves in a circular path concentric with the axis of shaft 37. Since the entire frame 48 rotates, the vertical shaft 60 is constrained to rotate with the frame, namely, to describe a circular path, but is also reciprocated longitudinally of the frame due to the linkage, comprising arm 61 and rod 65, connecting shaft 60 to the rotating arm 49. Thus, the pivot point defined by the ball 63 rotates and oscillates as the vertical shaft 66 moves in the aforesaid circular path, causing the parallel angle bars 58 to slide back and forth along the bars 57, meanwhile rotating with the frame 48. The resultant of the combined circular and reciprocating movements of the shaft 60 is a rotating varying substantially closed-loop path such as 60a or 60b in FIGURES 14A, 14B or 14C, whose parameters vary with time and are determined by the effective radius of the circular path of shaft 66, the effective length of the links defined by the rod 65, namely, the distance between shaft 66 and the adjustable pivot bracket 64, and the length of the link defined between the axis of shaft 60 and the pivot ball 63, namely, defined by the adjustment of the member 62 on the arm 61.

The upper optical blank, shown at 68, is cemented to a supporting disc 69 which is rotatably connected, by a universal joint 70, to a vertical shaft 71 to the top portion of which is secured a pulley 72. A vertical sleeve 73 rotatably receives the shaft 71, said sleeve 73 being rigidly secured between the ends of a pair of angle bars 74, 74 which extend horizontally, substantially parallel to each other. A vertical sleeve 75 is pivotally secured between the opposite end portions of the angle bars 74, 74, said sleeve 75 rotatably receiving the vertical sleeve 59. The angle bars 74, 74 are transversely connected by fastening bolts 76 at spaced points therealong.

Adjustably secured, as by a clamping bracket 77, to an upstanding vertical post 78 provided on frame 16 is a horizontal inwardly extending rod 79 which is provided at its inner end with an upstanding vertical shaft portion 80 extending between the angle bars 74, 74, said shaft portion being rotatably and slidably received in a vertical sleeve 81 welded between a pair of right angled bracket sleeves 82, 82 slidably engaged on the bars 74, 74.

As shown in FIGURE 2, the bracket member 77 comprises a clamping sleeve adjustably mounted on the vertical post 78 provided with a horizontal sleeve portion which is clampingly engageable with the rod 79, so that the location of the vertical shaft, or fulcrum 80 may be adjusted horizontally, as well as vertically.

Due to the pivotal and sliding connection between the fixed vertical shaft 80 and the bars 74, 74, the resultant path of movement of the vertical shaft 71 is governed by the path of movement of the shaft 60. Thus, since the shaft 60 moves in a rotating substantially closed-loop path, the shaft 71 likewise moves in a rotating substantially closed-loop path controlled by the path of the shaft 60

and with parameters depending upon the relationship of the radial distance between shaft 60 and pivot shaft 80 and that between pivot shaft 80 and shaft 71. Thus, with the pivot shaft 80 in the leftward position of FIGURE 14A, shaft 71 moves in laterally elongated substantially closed-loop paths such as 71a or 71b in FIGURE 14A. With pivot shaft 80 in the intermediate position thereof shown in FIGURE 14B, shaft 71 moves in relatively non-elongated substantially closed-loop paths such as 171a or 171b in FIGURE 14B. With pivot shaft 80 in the rightward position thereof shown in FIGURE 14C, shaft 71 moves in a longitudinally elongated substantially closed-loop path such as 271a or 271b in FIGURE 14C.

It will be noted that each blank 68 and 23 is provided with a similar supporting disc 69 and 69' having bracket means for interchangeable connection in the universal joint 70 so that the blanks may be interchanged without the necessity of removing and recementing their supporting discs thereof.

The sleeve member 75 which comprises the bearing support for the members 74, 74 is rotatably supported on the top flanges of the members 58, 58. Designated at 84 is a channel-shaped member provided with upper and lower pairs of spaced horizontally extending arms 85, 85 and 86, 86 which slidably receive a vertical bearing sleeve member 87 which is supportingly connected to a sleeve member 88, rotatably receiving the shaft 60, by a turn buckle assembly 89. As shown in FIGURE 5, the sleeve 88 is rotatably supported on the top edge of the sleeve 59.

Journaled in the sleeve 87 is a vertical shaft 90 to the top and bottom portions of which are journaled the respective pulleys 91 and 92, retaining collars 93 and 94 being secured on the shaft 90 above and below the respective pulleys 91 and 92, as shown in FIGURE 5. The pulley 91 is drivingly coupled by a belt 95 to a substantially larger pulley 96 secured on the top portion of shaft 60. The pulley 92 is drivingly coupled by a belt 97 to a pulley 98 which is secured on the upper portion of sleeve 59, immediately above the bearing sleeve 75. The pulley 98 is slightly smaller than the upper pulley 96. The turn buckle assembly 89 is adjusted so that the pulleys 91 and 92 are urged outwardly with sufficient force to maintain substantial tension in the belts 95 and 97, the outward horizontal force exerted on the sleeve 87 creating said tension, and the forces in the belts 95 and 97 being substantially balanced. The tension in the belts 95 and 97 acts to maintain the shaft 90 vertical and also the balance of tensions includes a sufficient supporting component to maintain the turn buckle assembly 89 substantially horizontal and the bearing sleeve 87 substantially vertical.

Rigidly secured to the guide member 84 is an elongated supporting rod 99 which extends parallel to the turn buckle assembly 89 and projects sufficiently to overlie the slot defined between the members 74, 74. Rod 99 is rigidly secured to sleeve 88 by an arm 107. A vertical depending rod member 100 is rigidly secured to the end of the elongated rod 99, said depending rod 100 extending between the arms 74, 74 so that the position of the guide bracket member 84 is positively controlled and is held fixed with respect to the arms 74, 74, since the rod 99 is connected to the sleeve 88 which is coaxial with shaft 60, and the depending rod 100 does not move in a longitudinal direction between the members 74, 74. The depending rod element 100 thus constrains the bracket member 84 to remain in a fixed horizontal position with respect to the arms 74, 74, whereby the structure controlled by the bracket member 84, namely, the shaft 90, the pulleys 91, 92, the turn buckle assembly 89, and the parts associated with these elements are held against horizontal movement with respect to the members 74, 74.

Secured on the shaft 60 immediately below the pulley 96 and being freely rotatable with respect to the sleeve 88 is a relatively small pulley 101 which is drivingly coupled by a belt 102 with the relatively large pulley 72

secured to the top end portion of shaft 71. Belt 102 transmits torque from shaft 60 to shaft 71, so that the blank 68 is rotated simultaneously with the rotation of shaft 60, but at a substantially slower speed. Thus, the blank 68 rotates around the vertical axis of shaft 71 and is simultaneously moved in the orbital closed-loop path above described. Thus, assuming counterclockwise rotation of the frame member 48, as viewed in FIGURES 6 and 7, the frame member 48 may be considered as having a starting position wherein it is aligned with the slot defined between the members 74, 74, under which conditions the blank 68 will be at its position of maximum displacement to the left, as viewed in FIGURES 2 and 6. Rotation of the frame 48 from the position of FIGURE 6 to the position of FIGURE 7 causes the arm 65 to be swung around the shaft 66 from the position of FIGURE 6, wherein it is directed upwardly and to the left, to the position of FIGURE 7, wherein it is directed upwardly and to the right, the frame 48 having moved through an angle of approximately 135° in a counterclockwise direction. The action of the linkage elements connecting frame 49 to shaft 60 and the pivoted lever structure, comprising arms 74, 74, connecting sleeve 75 to sleeve 73 causes the rotating blank 68 to shift correspondingly from the position of FIGURE 6 to the position of FIGURE 7. The blank 68, while rotating, moves through a rotating orbital path, shown for example in dotted view at 104 in FIGURE 7, providing a lapping cooperation between the rotating and orbitally moving upper blank 68 and the rotating lower blank 23.

Due to the continuous relative movement between the upper blank 68 and the rotating bottom blank 23, the abrasive material, which is supplied in a conventional manner so that it may be received between the bottom surface of the upper blank 68 and the top surface of the lower blank 23, acts with maximum efficiency and uniformity of abrading action.

In accordance with the present invention, the member 23 may comprise a form or molding element and the member 68 may be a work piece whose surface is to be ground according to the upper configuration of the forming member 23. However, in the preferred application of the present invention, both members 23 and 68 comprise blanks, with the top surface of the member 23 and the bottom surface of the member 68 being simultaneously ground and worked to a spherical contour. By suitably adjusting the position of the vertical pivot shaft 80, as well as by suitably adjusting the various elements of the driving linkage associated with the transmission of driving force from the shaft 37 to the shaft 60, the abrading force exerted between the upper member 68 and the lower member 23 may be so applied as to effect zonal corrections of deviations for a desired type of curve and to eliminate unwanted zonal deviations. Thus, initially, the surfaces between the members 23 and 68 may be flat and horizontal. By suitably adjusting the position of the vertical pivot shaft 80, and by suitably adjusting the position of pivot shaft 66 relatively to the axis of shaft 37, the position of member 64 on rod 65, and the position of member 62 on arm 61, the apparatus may be employed to grind spherical surfaces of desired curvature between the members 23 and 68. Thus, the top surface of the member 23 may be ground to a convex shape, whereas the bottom surface of the member 68 may be ground to a concave shape.

FIGURES 6 and 7 show why spherical surfaces are ground between the members 68 and 23. It will be seen from FIGURES 6 and 7 that the movement of the upper member 68 takes place around an orbital axis path wherein the upper member 68 generally projects laterally over the periphery of the lower member 23 and rotates and oscillates continuously, so that it is generally off center with respect to the lower member 23, for example, moving from the starting position shown in FIGURE 6 in full line view and in FIGURE 7 in dotted view, to

the full line position shown in FIGURE 7, having moved in a counterclockwise direction, as viewed in FIGURES 6 and 7. As a result, the abrading action is heavier adjacent the periphery of the lower member and in the center portion of the upper member than in the center portion of the lower member and the periphery of the upper member, the degree of difference depending upon the various adjustments above mentioned, since these adjustments determine the amount of throw of the upper member 68 relative to the bottom member 23, and upon the coarseness of the abrasive used.

FIGURES 8, 9, 10, 11, 14A, 14B and 14C indicate clearly that the amount of displacement or throw, provided for the various linkage elements, and ultimately applied to the shaft member 71, depends upon the length of the various link arms involved in the transmission of the driving torque from the shaft 37 to the lever elements 74, 74, and the degree of excursion of the shaft 71 is further dependent upon the position of the fulcrum shaft 80 in the slot defined between the members 74, 74.

FIGURE 12 illustrates the type of resultant surfaces which may be obtained by suitable adjustment of the above-mentioned members of the machine, and clearly illustrates how the blank 68 may move in its orbital path around the lower form or blank 23 so that it constantly moves orbitally along the periphery of the lower member 23 and extends laterally over said periphery. Thus, FIGURE 12 shows the upper blank 68 in a position corresponding to that shown in FIGURE 6, and also shows in dotted view the position of the upper blank 68 corresponding to that shown in FIGURE 7. It will be seen that the member 68 has been ground so that its bottom surface 105 is spherically concave, whereas the top surface of the lower blank 23, shown at 106, has been ground so that it is spherically convex.

The shaft 71 may be adjusted in a direction in a line including shaft 37 and shaft 80. This adjustment does not accomplish the same thing as a lateral adjustment of the shaft 80, since the path of the shaft 71 (such as 271a in FIGURE 14C) may be elongated and the speed of shaft 71 around its path is not constant. Since the path of shaft 71 (such as 271a) has bilateral symmetry, lateral displacement of this path will not provide the same relative motions between the upper and lower blanks as will a displacement of this path along a direction in line with shafts 37 and 80.

While a specific embodiment of an improved grinding and polishing machine for optical elements, such as lenses, mirrors, or the like, has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A grinding and polishing machine comprising a support, a horizontal bottom tray member, means to rotate said bottom tray member around a vertical axis, means on said bottom tray member to support a lower blank for coaxial rotation therewith, a horizontal arm, means slidably and pivotally supporting said arm on said support with one end thereof extending over said bottom tray member, means on said one end to rotatably support an upper blank adjacent and in overlying relation to said bottom tray member, means to rotate said last-named supporting means, and means driving the other end of said arm in a substantially closed-loop path substantially in a horizontal plane.

2. A grinding and polishing machine comprising a support, a horizontal bottom tray member, means to rotate said bottom tray member around a vertical axis, a central supporting block on said tray member, means on said central supporting block to support a lower blank for coaxial rotation therewith, a horizontal arm, means slidably and pivotally supporting said arm on said support

with one end thereof extending over said central supporting block, means on said one end to rotatably support an upper blank adjacent and in overlying relation to said central supporting block, means to rotate said last-named supporting means, and means driving the other end of said arm in a substantially closed-loop path substantially in a horizontal plane.

3. In a grinding and polishing machine comprising a support, a horizontal bottom tray member, means to rotate said bottom tray member around a vertical axis, means on said support, means on said bottom tray member to support a lower blank for coaxial rotation therewith, a horizontal arm, means slidably and pivotally supporting said arm on said support with one end thereof extending over said bottom tray member, means on said one end to rotatably support an upper blank adjacent and in overlying relation to said bottom tray member, means to rotate said last-named supporting means, a vertical, horizontally elongated frame rotatably mounted on said support, and means drivingly coupling said frame to the other end of said arm and driving the other end of said arm in a closed-loop path substantially in a horizontal plane.

4. In a grinding and polishing machine comprising a support, a horizontal bottom tray member rotatably mounted on said support, means to rotate said bottom tray member around a vertical axis, means on said bottom tray member to support a lower blank for coaxial rotation therewith, a horizontal arm means slidably and pivotally supporting said arm on said support with one end thereof extending over said bottom tray member, means on said one end to rotatably support an upper blank adjacent and in overlying relation to said bottom tray member, means to rotate said last-named supporting means, a vertical driving shaft journaled on said support, horizontally extending crank means secured to said shaft, means slidably connecting the other end of said arm to said crank means, and a linkage interconnecting said last-named means and said crank means and cooperating with said crank means to drive said other end of the arm in a closed-loop path substantially in a horizontal plane.

5. A grinding and polishing machine comprising a support, a horizontal tray member rotatably mounted on said support, means to rotate said bottom tray member around a vertical axis, means on said bottom tray member to support a lower blank for coaxial rotation therewith, a horizontal arm, means slidably and pivotally supporting said arm on said support with one end thereof extending over said bottom tray member, means on said one end to rotatably support an upper blank adjacent and in overlying relation to said bottom tray member, means to rotate said last-named supporting means, a vertical driving shaft journaled on said support, a vertical horizontally elongated crank frame secured on said shaft, means slidably connecting the other end of said arm to said crank frame, and a pair of link members interconnecting said last-named means and said crank frame and arranged to reciprocate said last-named means along said frame responsive to rotation of the shaft, whereby to drive said other end of the arm in a closed-loop path substantially in a horizontal plane.

6. A grinding and polishing machine comprising a support, a horizontal tray member rotatably mounted on said support, means to rotate said bottom tray member around a vertical axis, means on said bottom tray member to support a lower blank for coaxial rotation therewith, a horizontal arm, means slidably and pivotally supporting said arm on said support with one end thereof extending over said bottom tray member, means on said one end to rotatably support an upper blank adjacent and in overlying relation to said bottom tray member, a vertical driving shaft journaled on said support, a vertical horizontally elongated crank frame secured on said shaft, means slidably connecting the other end of said arm to said crank frame, a pair of link members interconnecting said last-named means and said crank frame and arranged

to reciprocate said last-named means along said frame responsive to rotation of the shaft, whereby to drive said other end of the arm in a closed-loop path substantially in a horizontal plane, vertical shaft means drivingly connected to one of said link members, and means drivingly coupling said last-named vertical shaft means to said last-named supporting means.

7. A grinding and polishing machine comprising a support, a horizontal bottom tray member rotatably mounted on said support, means to rotate said bottom tray member around a vertical axis, means on said bottom tray member to support a lower blank for coaxial rotation therewith, a horizontal arm, means slidably and pivotally supporting said arm on said support with one end thereof extending over said bottom tray member, means on said one end to rotatably support an upper blank adjacent and in overlying relation to said bottom tray member, a vertical driving shaft journaled on said support, a vertical horizontally elongated crank frame secured on said shaft, means including a vertical sleeve slidably connecting the other end of said arm to said crank frame, a pair of link members interconnecting said last-named means and said crank frame and arranged to reciprocate said last-named means along said frame responsive to rotation of the shaft, whereby to drive said other end of the arm in a closed-loop path substantially in a horizontal plane, vertical shaft means journaled in said vertical sleeve and drivingly connected to one of said link members, and means drivingly coupling said last-named vertical shaft means to said last-named supporting means.

8. A grinding and polishing machine comprising a support, a horizontal bottom tray member rotatably mounted on said support, means to rotate said bottom tray member, means on said bottom tray member to support a lower blank for coaxial rotation therewith, a horizontal arm, vertical pivot means on said support, said arm being formed with longitudinal slot means slidably receiving said vertical pivot means, whereby the arm slidably and pivotally engages said vertical pivot means, said pivot means being located so that one end of said arm overlies said bottom tray member, means on said one end to rotatably support an upper blank, adjacent and in overlying relation to said bottom tray member, means rotating said last-named supporting means, a vertical driving shaft on said support, and means coupling said driving shaft to the other end of said arm and driving said other end in a closed-loop path in a horizontal plane.

9. A grinding and polishing machine comprising a support, a horizontal bottom tray member rotatably mounted on said support, means to rotate said bottom tray member, means on said bottom tray member to support a lower blank for coaxial rotation therewith, a horizontal arm, vertical pivot means on said support, said arm being formed with longitudinal slot means slidably receiving said vertical pivot means, whereby the arm slidably and pivotally engages said vertical pivot means, said pivot means being located so that one end of said arm overlies said bottom tray member, means on said one end to rotatably support an upper blank adjacent and in overlying relation to said bottom tray member, a vertical driving shaft on said support, means coupling said driving shaft to the other end of said arm and driving said other end in a closed-loop path in a horizontal plane, and means drivingly coupling said vertical driving shaft to said means to support the upper blank.

10. A grinding and polishing machine comprising a support, a horizontal bottom tray member rotatably mounted on said support, means to rotate said bottom tray member, means on said bottom tray member to support a lower blank for coaxial rotation therewith, a horizontal arm, vertical pivot means on said support, said arm being formed with longitudinal slot means slidably receiving said vertical pivot means, whereby the arm slidably and pivotally engages said vertical pivot means, said pivot means being located so that one end of said arm overlies

said bottom tray member, means on said one end to rotatably support an upper blank adjacent and in overlying relation to said bottom tray member, a vertical driving shaft on said support, crank means interconnecting said vertical driving shaft and the other end of said arm and moving said other end of the arm in a horizontal plane in a closed-loop path around the axis of said vertical driving shaft, vertical shaft means extending rotatably through said other end of the arm and connected to said crank means, and means drivingly connecting said last-named vertical shaft means to said means to support the upper blank.

11. An optical grinding and polishing machine comprising a support, a horizontal bottom tray member rotatably mounted on said support for rotation around a vertical axis, means to rotate said bottom tray member, upstanding pin means on the central portion of said bottom tray member defining an enclosure to receive a lower blank and to support same for coaxial rotation with said bottom tray member, a longitudinally slotted horizontal arm, vertical pivot means on said support above and adjacent said bottom tray member, said pivot means engaging in the slot of said horizontal arm, whereby the arm is slidably and pivotally engaged with said pivot means, with one end of said arm overlying the central portion of the tray member, vertical shaft means on said one end adapted to rotatably support an upper blank in overlying relation to a lower blank in said enclosure, means rotating said vertical shaft means, a vertical driving shaft on said support, and means coupling said driving shaft to said other end of the arm and being arranged to drive said other end in a closed-loop path in a horizontal plane.

12. An optical grinding and polishing machine comprising a support, a horizontal bottom tray member rotatably mounted on said support for rotation around a vertical axis, means to rotate said bottom tray member, upstanding pin means on the central portion of said bottom tray member defining an enclosure to receive a lower blank and to support same for coaxial rotation with said bottom tray member, a longitudinally slotted horizontal arm, vertical pivot means on said support above and adjacent said bottom tray member, said pivot means engaging in the slot of said horizontal arm, whereby the arm is slidably and pivotally engaged with said pivot means, with one end of said arm overlying the central portion of the tray member, vertical shaft means on said one end adapted to rotatably support an upper blank in overlying relation to a lower blank in said enclosure, means rotating said vertical shaft means, a vertical driving shaft on said support, a vertical horizontally elongated rectangular frame having its bottom portion secured on said driving shaft, means slidably and pivotally connecting the other end of said arm to the top portion of said frame, and link means interconnecting said last-named means and said bottom portion of the frame and being arranged to reciprocate said last-named means along said frame top portion responsive to rotation of the driving shaft, whereby to drive said other end of the arm in a closed-loop path in a horizontal plane.

13. An optical grinding and polishing machine comprising a support, a horizontal bottom tray member rotatably mounted on said support for rotation around a vertical axis, means to rotate said bottom tray member, upstanding pin means on the central portion of said bottom tray member defining an enclosure to receive a lower blank and to support same for coaxial rotation with said bottom tray member, a longitudinally slotted horizontal arm, vertical pivot means on said support above and adjacent said bottom tray member, said pivot means engaging in the slot of said horizontal arm, whereby the arm is slidably and pivotally engaged with said pivot means, with one end of said arm overlying the central portion of the tray member, vertical shaft means on said one end adapted to rotatably support an upper blank in overlying relation to a lower blank in said enclosure, a vertical driving shaft

on said support, a vertical horizontally elongated rectangular frame having its bottom portion secured on said driving shaft, means including a vertical sleeve slidably and pivotally connecting the other end of said arm to the top portion of said frame, link means interconnecting said last-named means and said bottom portion of the frame and being arranged to reciprocate said last-named means along said frame top portion responsive to rotation of the driving shaft, whereby to drive said other end of the arm in a closed-loop path in a horizontal plane, a shaft jour-
